PAGE 3

Figure 1 is a front elevational view of a local battery wall telephone set, showing our new design;

Figure 2 is a side elevational view, the opposite side being a substantial mirror image thereof with exception of the crank;

Figure 3 is a top plan view; and

Figure 4 is a bottom plan view thereof.

The characteristic features of our design reside in the portions shown by means of full lines in the drawings.

We claim:

The ornamental design for a local battery wall telephone set, as shown and described.
